UNITED STATES PATENT OFFICE.

JOSIAH B. MILLET, OF BOSTON, MASSACHUSETTS, ASSIGNOR TO MILLET SIGNAL COMPANY, OF BOSTON, MASSACHUSETTS, A CORPORATION OF MAINE.

SUBMARINE SIGNALING.

933,720.

Specification of Letters Patent.

Patented Sept. 7, 1909.

Application filed May 18, 1909. Serial No. 496,761.

To all whom it may concern:

Be it known that I, JOSIAH B. MILLET, a citizen of the United States, and a resident of Boston, in the county of Suffolk and 5 Commonwealth of Massachusetts, have invented an Improvement in Submarine Signaling, of which the following description, in connection with the accompanying drawings, is a specification, like characters on 10 the drawings representing like parts.

My invention relates to the art of submarine signaling, and aims to produce a signaling apparatus capable of transmitting and detecting those sounds or sound waves 15 which are desirable or necessary for the successful use of the signaling system, while excluding such sounds or sound waves as would produce a disturbing and confusing result.

20 Prior to my invention submarine signaling apparatus of the type commonly used have employed a microphonic device to amplify and transmit the sound waves constituting the signal, and as heretofore commonly organized, such systems have been 25 subject to comparatively early loss of efficiency due to the packing of the microphonic material or substance, which my present invention, among other things, aims 30 to prevent. In systems at the present in use, there is also great lack of efficiency due to the inability of the apparatus to distinguish or select those sound waves constituting the signal proper which the observer desires to 35 receive from such sound waves as do not constitute a part of the desired signal or information, and the presence of which constitute a serious disturbing factor. This difficulty my invention aims to overcome in 40 the manner that will be more clearly understood from the following disclosure of a selected embodiment of my invention. So also other features and phases of my invention will be better understood from the following disclosure of one embodiment of my 45 invention.

In the accompanying drawings, Figure 1 represents diagrammatically the selected embodiment of my invention referred to; Fig. 50 2, in enlarged section, shows the microphonic transmitting apparatus shown in Fig. 1; Fig. 3, a transverse sectional detail on the dotted line 3—3, Fig. 2, looking downward; and Figs. 4 and 5, diagrammatic views to be 55 referred to.

Referring to the drawing, and first to Fig. 1, I have typified at the left any usual or suitable submarine bell or sound producing signal apparatus S, and at the right of said figure is indicated in partial transverse section the hull of a vessel V, upon which the signals are to be received and availed of.

Referring now particularly to Fig. 2, which is a longitudinal, approximately horizontal, sectional view looking downward, the plating or skin of the ship is still indicated by the reference letter V. At the upper portion of said figure is a longitudinal brace or yoke V' supported in any suitable manner against or upon the ship's skin or plating 60 and conveniently secured to and between the ship's ribs. This yoke is shown provided with an aperture V². Interposed between the yoke V' and the ship's skin V is a cup shaped or flaring casing or holder 1 of suitable or desired shape and material, conveniently of metal. At its open end, which is presented to the ship's side, said casing is adapted to receive yieldable means, such as rubber packing 2 for the purpose of acoustically insulating the casing from the ship's plating V and also for facilitating adjustment of the casing toward the said plating. To press the casing firmly against the packing 70 any suitable means may be employed, conveniently three set screws or bolts 4 screwed into and through the yoke V' and acting against the inner end of the casing. By means of these screws the casing may be evenly and firmly pressed toward the ship's plate and 75 adjusted to conform to any inequality of such plate, the screws being held against loosening by lock nuts 5 or other suitable means. Instead of arranging the set screws 80 to act directly upon the casing itself, I prefer to employ a separate contact ring 6 supported by but insulated from the casing proper, as by a rubber ring or washer 7, the idea being to insure not only proper supporting contact but to prevent the transmission 85 of sound vibrations that might constitute a disturbing factor in the use of the system.

Within the holder 1, I have arranged the electromechanical microphonic device, the same comprising, as herein shown, a usual or suitable granular microphonic button 8. As shown, this button comprises the contact electrodes 9 and 10, between which is arranged the granular contact material 11, as 90 100 105 110

is usual in microphonic devices. This button is suitably supported within a box 12, preferably of metal, and preferably having thick walls, one of which, as 13, may be removable and screwed into place to furnish access when desired to the inclosed microphonic button. This microphonic box 12 is provided with a stem 14 which extends inward through the inclosed end of the casing 1. Said inclosed end of the casing 1 is provided with a projection 1' which has extending therethrough an opening 1² in which is placed an adjusting nut 15, by means of which said box may be pressed into firm contact with the plate or skin of the ship or into contact with any sound conducting non-gaseous substance itself acoustically connected to the skin of the ship through an intervening non-gaseous sound conductor or conductors, whereby the box may receive sound vibration by contact either directly or indirectly from the ship's skin. Preferably I provide the microphonic box 12 with a contact point 17 conveniently of conical shape and screwed into or otherwise secured to the said box with its pointed end resting in contact with the ship's plate or skin as shown, and this point may be pressed against the plate or skin with any desired pressure by means of the nuts 15, 16 described. The threaded box stem 14 may be provided with a longitudinal groove 18 at the left of Fig. 2 to receive an inwardly projected pin 19 on the closed end of the casing to prevent relative rotation of the box and casing and thus facilitate making and maintenance of adjustment. The use of a point or other penetrative contact member is preferable since it permits the penetration of rust or other film or coating on the plating or on the other body with which contact is sought, thereby securing a good contact. The contact secured also is a localized one of small delivery surface but presented in the most effective position to cause response to the submarine sound waves impinging against the ship's skin. The electrical conductors 19, 20 may be connected as shown, one to the stem of the casing and the other carried through an insulated conduit in the threaded stem 14 to and connected with the electrode 9, which is not connected with the box, so that any vibration received by contact through the wall of the box will cause more or less compression of the granular microphonic material 11, and thus induce a variable response through the electrodes 9 and 10 in the electrical circuit which includes the conductors 19 and 20. These conductors as indicated in Fig. 1, may be connected with a battery B and receiver R located at any convenient point or points. In practice, the ship is preferably equipped with a plurality of these microphonic transmitters arranged at and in acoustical connection with oppo-

site sides of the ship relative to its longitudinal median line and connected respectively with receivers which will permit of a comparison of signaling sounds transmitted to and through the respective transmitters, being thus used in a manner well understood by those conversant with the art. 70

It will be observed that the electrodes 9, 10, between which the microphonic material is placed, stand in approximately vertical positions and transversely of the ship; that is to say, they stand in planes which are substantially parallel with the transverse plane or planes of rolling motion of the ship, which are the planes ordinarily of maximum ship's motion. The ship usually rolls to a greater degree than it pitches, and in any motion of the ship, however complex, the rolling motion averages to be the more pronounced. 80

Referring now to the diagrams, Figs. 4 and 5, it will be observed that in Fig. 4, showing the ship in one angular position of roll indicated by the dotted line $q-q$, the level of the granular microphonic material 90 is indicated by the letters $q'-q'$ extending between the points $x-x$ of the microphonic device. When now the ship rolls to an opposite angular position indicated by Fig. 5, it will be observed that the level of the microphonic material shifts so as to extend between the points $x'-x'$. The rolling of the ship from its position Fig. 4 to that of Fig. 5 has caused the entire mass of granular microphonic material to change its position between the electrodes 9 and 10 in order to take up its new level, the rolling of the ship serving really to turn or roll the inclosure for the microphonic material under and about the same to enable the latter to take up its new 105 relative position between the electrodes with the result that the entire mass while keeping substantially the same relation with the electrodes is maintained by the motion of the ship in a permanently loose and free condition substantially that in which it was originally introduced into the apparatus. 110

Heretofore where a diaphragmatic support for the microphone button has been employed, it has been deemed necessary to arrange the microphonic device flat against the ship or longitudinally thereof, where its electrodes are transverse to the plane or planes of maximum ship's motion. Under these circumstances the effect of the rolling 120 of the ship is to tip these side walls or electrodes back and forth laterally about their lower edges as pivots, with the result that the mass of microphonic material between them is subjected to very little disturbing 125 action, and quickly packs. This reduces the efficiency of the system and, because not subjected to any constant agitating action, one microphone at one side of the ship may pack to a greater extent than the other, imme- 130

diately throwing the system out of balance and rendering the system as a whole unreliable. Moreover such motion as the microphone receives from the rolling of the ship 5 acts to change the contact relations between the microphonic material and the electrodes without assisting in preventing the packing of the said material. The difference is in the mounting of a microphonic device so as 10 to cause in the one case, as herein, a movement of substantially the entire mass of granular material bodily between its opposed electrodes and the action as heretofore of tipping the mass first in one and then in 15 the opposite direction without enforcing any bodily movement thereof between and relative to its electrodes. It will be seen that where a non-diaphragmatic contact wall is employed to transmit the submarine vibrations 20 to the microphone the position of the microphone may be selected at will and, as herein, the latter may be mounted in a transverse plane without in any way diminishing its sensitiveness. This novel mounting of 25 the microphonic device with the microphonic material between walls which are arranged substantially in the plane or planes of maximum ship's motion thus serves to prolong the period of highest efficiency of 30 the system so far as such efficiency is dependent upon the condition of the microphone and constitutes I believe a very important improvement in the art.

I do not herein claim the novel method 35 for utilizing the rolling motion of the ship to agitate the granules, as described, the claims herein being confined to the apparatus. Claims for the method are included in another co-pending application.

40 In a submarine signaling apparatus, conditions are such as to make it essential that the sound transmitting means shall be responsive to and transmit the most minute sound waves or sound vibrations which 45 emanate from the signaling bell or other source of sound which it is desired to detect or locate, such for example as the sounds of the screws of another steamer; and to this end it is important that the microphonic apparatus be most delicately organized and 50 adjusted. Unfortunately, however, the very delicacy and organization of the microphonic apparatus so important to detect signaling or other sounds or sound waves, such 55 as above mentioned, also render the apparatus more susceptible to the receiving and transmission of other and disturbing vibrations or sounds, for example, such as originate within or exist in the ship itself or the 60 air contained therein. I have discovered, that the sounds which originate or are contained in the ship's hold and which ordinarily constitute disturbing sounds in a submarine signaling system are usually transmitted 65 at some point through the air con-

tained within the ship, while those sounds which originate with the signaling bell or other source which it is desired to detect by means of the submarine signaling system originate in and are transmitted only 7 through the water or liquid. Recognizing this distinction, my present invention comprehends protecting the microphonic device against sound vibrations of air or gas so as to exclude such from the microphonic action 75 and arranging the microphonic device in contact with the skin of the ship or otherwise through a contact member of sound conducting material so that it will respond to sound waves or vibrations which exist in the 80 skin of the ship and those only, and which are produced by sound waves in the surrounding water. Preferably the inclosing walls of the box or casing 12 are of such material and thickness as to exclude substantially 85 all disturbing sounds propagated through gaseous media, there being provided, however, a contact member or sound conducting portion in acoustical contact with the microphone and adapted to be applied 90 to the non-gaseous body in which sound vibrations are to be detected. Preferably, also, though not necessarily, the box or casing is of metal and the walls are of such thickness in proportion to their exposed 95 superficial area that the inclosure cannot act as a diaphragm in response to air or other gaseous vibrations.

Referring to Fig. 2 of the drawing, it will be observed that the inclosing box for the 100 microphone is thick walled and substantially unresponsive to external air vibrations, but that through a contact connection, such as the point 17 said box responds to the vibrations of the ship's skin which reliably 105 transmit the submarine or other signal or sound which it is desired to detect.

It will be seen that the rubber packing 2 not only acts as an insulation, preventing 110 the entrance within the casing 1 of sounds 1 propagated through the air, and not only serves as a yielding wall or abutment which, by application to the ship's skin, permits obtaining the requisite contact on the application of pressure to the holder, but also 115 serves another purpose in that it prevents the submarine sound waves impinging against the ship's skin from being transmitted to the holder, and thereby prevents the tendency of the holder and the casing 13 to 120 vibrate in unison with the ship's skin and the counteraction of the vibrations received through the contact member 17. Substantially all sound vibrations, therefore, reaching 125 the casing are transmitted through the contact member 17.

Having described one embodiment of my invention and without limiting myself to inconsequential details, what I claim and desire to secure by Letters Patent is,— 130

1. A submarine signaling system, comprising in combination a submarine sound-producer, an electro-microphonic sound-detection and transmission device inclosed by walls of suitable material and thickness to exclude substantially all disturbing sounds propagated through gaseous media, said walls providing a sound-conducting portion in acoustic contact with the microphonic device to transmit to the latter sound vibrations received by contact with solid or liquid media only, and a receiver electrically connected with said microphonic device.

2. In a submarine signaling system, the combination with a submarine sound producer, of a ship's hull, an electro-microphonic sound detection and transmission device, inclosed by walls of suitable material and thickness to exclude substantially all disturbing sounds propagated through gaseous media, said device having a sound-conducting portion in acoustical contact with the microphone and also with the ship's hull, or a part acoustically connected thereto, thereby to transmit sound vibrations from the ship's hull to the microphone, and a receiver electrically connected with said microphone device.

3. In a submarine signaling system, the combination with a submarine sound producer of a ship's hull, an electro-microphonic sound detection and transmission device, said device being inclosed by walls of suitable material and thickness to protect it against access of sound vibrations other than those received through a conducting body, said inclosure indicating a solid non-diaphragmatic sound conducting body in acoustical contact with said microphone said sound conducting body being adapted to contact with the ship's skin or a part acoustically connected thereto, and a receiver electrically connected with said microphone.

4. In a submarine signaling apparatus an electro-microphonic device, a gaseous sound-wave-excluding casing for the same with which said device is in acoustical contact and an exterior point contact for said casing.

5. In a submarine signaling apparatus the combination with the ship's hull, an electro-microphonic device, a contact wall in acoustical contact with said device, and means for adjustably applying the said wall by contact to the ship's skin or other solid body acoustically connected thereto.

6. In a submarine signaling apparatus the combination with a ship's hull, of a microphone, a sound conducting body acoustically connected thereto, said microphone being protected against the access of sound vibrations other than those received through said body, and means for pressing the body against the ship's skin or a part acoustically connected thereto.

65 7. In a submarine signaling apparatus the

combination with a ship's hull, a microphone device having a contact wall, a holder, a yieldable member, means to press the holder against the ship's skin or a part acoustically connected thereto through the intervening yieldable member to secure contact by the contact wall.

8. In a submarine signaling apparatus the combination with a ship's hull, a microphone device, a sound conducting body acoustically connected thereto, a holder, means to adjust the holder to obtain contact between the body and the ship's hull or a part acoustically connected thereto, and means to adjust the conducting body and the holder.

9. In a submarine signaling system the combination with a submarine sound producer of a microphonic detection and transmission device, a metallic casing inclosing said device, said casing having its walls of sufficient thickness in proportion to its external dimensions to exclude substantially all disturbing sounds propagated through gaseous media, and a receiver electrically connected to the microphone.

10. In a submarine signaling system the combination with a submarine sound detector, of a microphonic detection and transmission device inclosed by walls of sufficient thickness in proportion to their exposed superficial dimensions to exclude substantially all disturbing sounds propagated through gaseous media, said walls providing a sound conducting portion in acoustical contact with the microphonic device, and having an exteriorly exposed part adapted to contact with the body in which the detection of sound vibrations is sought, and a receiver electrically connected with said microphonic device.

11. In a submarine signaling system the combination with a ship's hull, of an instrument having an electro-microphonic sound detection and transmission device inclosed by walls of suitable material and thickness to exclude substantially all disturbing sounds propagated through gaseous media said walls providing a sound conducting portion in acoustic contact with the microphonic device to transmit to the latter sound vibrations received by contact with solid or liquid media only, a support for said instrument to maintain the conducting portion in acoustical contact with the ship's hull, and means for acoustically insulating the instrument from the support.

12. In a submarine signaling system the combination with a ship's hull, of an instrument having an electro-microphonic sound detection and transmission device inclosed by walls of suitable material and thickness to exclude substantially all disturbing sounds propagated through gaseous media said walls providing a sound conducting portion in acoustic contact with the microphonic de-

vice to transmit to the latter sound vibrations received by contact with solid or liquid media only, a holder for said instrument, a support for the holder, means acoustically 5 to insulate the holder from the ship's hull and from the support.

13. In a submarine signaling apparatus, the combination with an electro-microphonic sound detection and transmission device 10 8-11, the same being inclosed by the casing 12, having walls of suitable material and thickness to exclude substantially all disturbing sounds propagated through gaseous media and the exterior contact member 17 15 in acoustical contact with the microphone through the casing.

14. In a submarine signaling system, the combination with a ship's hull of a microphonic sound transmitting device comprising 20 electrodes and intermediate microphonic material, said electrodes being arranged substantially parallel to the plane of maximum ship's wave produced motion at the point of support.

25 15. In a submarine signaling system, the combination with a ship's hull of an electro-microphonic transmission device comprising substantially parallel electrode walls with an intervening mass of microphonic material, said device being arranged with said walls substantially transverse to the ship's skin to cause rolling of the ship to produce bodily movement of the microphonic material between and relative to its said walls.

35 16. In a submarine signaling system, the combination with a ship's hull of an electro-microphonic transmitting device comprising electrodes and intervening microphonic material, the device being in contact with a side 40 of the ship or a part acoustically connected thereto to receive sound waves impinging against the ship's side and said microphone being supported transversely the ship to cause the lateral rolling of the ship to agitate the microphone material while preserving substantially similar contact relations 45 between the said material and the electrodes.

17. In a submarine signaling system the combination with a ship's hull, of an electro-50 microphonic transmitting device, an inclosure for said device adapted to exclude sound waves propagated through gaseous media, a sound conducting wall of solid material in contact with the microphone and arranged to transmit thereto sounds received 55 by contact with the ship's hull or with a body acoustically connected thereto, said microphone having electrodes and intervening microphonic material and being so arranged 60 that the lateral rolling of the ship is caused to agitate the material while preserving substantially similar contact relations between the said material and the electrodes.

65 18. In a submarine signaling apparatus,

the combination with a submarine sound producer, of a ship's hull and a detection and transmission device having a penetrative contact member for contact with the ship's hull or a part acoustically connected therewith. 70

19. A sound detection apparatus for detecting sounds in a solid body comprising a microphonic detection and transmission device, having a penetrative contact wall 75 acoustically connected with the microphone and adapted for application to the solid body.

20. In a submarine signaling apparatus, a receiving apparatus comprising a microphone, a holder, a contact wall acoustically connected with the microphone and adapted for contact with the body to which said holder is applied, and means for acoustically insulating the holder from the body while 85 holding the contact wall in contact with the same.

21. In a sound detection device the combination with a microphone, of a contact member 90 acoustically connected with the microphone and adapted to have localized contact with a solid body, a part attached to the microphone adapted to be pressed against the body, and means for acoustically insulating said part therefrom. 95

22. In a submarine signaling apparatus the combination with a submarine sound producer, of a ship's hull, and a receiving device provided with a microphone and a contact member, the latter having a solid metallic 100 acoustical connection with the microphone, said contact member being adapted for contact with the ship's hull or a part acoustically connected therewith.

23. In a submarine signaling apparatus 105 the combination with a submarine sound producer, of a ship's hull, and a receiving device provided with a microphone and a contact member, the latter having a solid acoustical connection with the microphone, 110 said contact member being adapted for contact with the ship's hull or a part acoustically connected therewith.

24. In a sound detection device, a microphone having a projecting contact member 115 for contact with a solid body, and an inclosing open-ended casing provided with means for acoustically insulating the same from the part to which the contact member is applied. 120

25. In a sound detection device, a microphone having a projecting contact member for contact with a solid body, and an open-ended casing about the same.

26. The combination with a sound detection device, of a contact member, and a yieldable wall for application to a solid body, the latter permitting contact to be had between the contact member and the body on application of pressure to the yieldable wall. 125 130

27. A sound detection apparatus for detecting sounds in a solid body, comprising a microphonic detection and transmission device having a contact member acoustically connected with the microphone and shaped for point contact with a solid body with which the detection of sound is sought.
28. The combination with a submarine sound producer, of the ship's hull V, the microphone 8—11, the contact member 17,

and the solid intermediate acoustical connection 12.

In testimony whereof, I have signed my name to this specification, in the presence of two subscribing witnesses.

JOSIAH B. MILLET.
